FRUIT JUICER

Robert W. Schier, Northbrook, and Ronald W. Guttenberg, Chicago, Ill., assignors to Design Dynamics, Inc., Chicago, Ill., a corporation of Illinois

Application May 25, 1959, Serial No. 56,051

Term of patent 14 years

(Cl. D89—1)

Figure 1 is a perspective view of a fruit juicer embodying our novel design;

Figure 2 is a plan view of the juicer shown in Figure 1; and

Figure 3 is a front elevational view of the juicer shown in Figure 1.

We claim:

The ornamental design for a fruit juicer, substantially as shown.
